UNITED STATES PATENT OFFICE.

WILLIAM N. TITUS, OF ERIE, PENNSYLVANIA.

INTERNAL-EXPLOSIVE ENGINE.

Application filed January 9, 1926. Serial No. 80,303.

This invention relates to internal combustion engines, and particularly of the type known as two cycle engines, in which there is one explosion at each revolution of the crank shaft.

In carrying out my invention I use two working cylinders in which are the usual pistons from which connecting rods extend to oppositely disposed cranks on the crank shaft.

The working cylinders are mounted on a crank case which encloses the cranks on the crank shaft. Adjacent to the working cylinders is a cylinder and piston mechanism adapted to draw a measured volume of explosive fluid from a carburetor mechanism and force it into one of said working cylinders when the piston therein has completed its downward travel. This cylinder and piston mechanism is operated directly from the crank shaft of the engine, thus eliminating all valves, springs and cam-shafts, timing chains, gears and other parts necessary in the construction of an ordinary four cycle motor.

In this motor the two working cylinders do the work of four cylinders in a four cycle motor because there is an explosion in each working cylinder at each rotation of the crank shaft.

These and other features of my invention are hereinafter explained and pointed out, and are illustrated in the accompanying drawings in which:

Figure 1 is a plan view of an internal explosive motor embodying my invention.

Figure 2 is a side elevation of the same.

Figure 3 is a vertical section of one of the working cylinders on the line 3-3 in Fig. 2.

Fig. 4 is a longitudinal section of the same on the line 4-4 in Fig. 1.

Figure 5 is a vertical section of the feeder cylinder and piston mechanism of my invention on the line 5-5 in Fig. 1.

Figure 6 is a like view of said cylinder and piston mechanism with the piston at its lowermost point of travel.

Figure 7 is an enlarged view of the regulating tube with portions in section.

Figure 8 is a section of the same on the line 8-8 in Fig. 7.

In these drawings A indicates the crank case of my improved engine and A' indicates oil pans into which cranks on the crankshaft dip during their rotation. A²

is a bottom pan which encloses the under side of the crank-case A and is adapted to contain oil.

Within the crank case A are shaft bearings B in which a crank shaft B' is mounted. The shaft B is provided with cranks B². Mounted on the crank case are working cylinders C in which are working pistons C'. C² are pitman rods which are pivoted to the pistons C' and mounted on the cranks B² in the usual manner. The working cylinders C are provided with intake ports c see Figs. 3, which are uncovered by the pistons C' when they reach their lowermost point, and with exhaust ports c' which are somewhat higher than the intake ports c, so that they are uncovered by the pistons C' before the inlet ports c are uncovered by said pistons. The pistons C' are provided with deflectors c² which stand in front of the intake ports c when the pistons are at their lowest travel, as shown in Fig. 3, to deflect the incoming gas upward in the cylinder C, to drive out the burnt gas, in the usual manner. With this arrangement as shown in Fig. 4, the working pistons act alternately, when one of said pistons is at the uppermost point of its travel, the opposite one is at its lowermost point. The exhaust ports c' communicate with an exhaust manifold D in the usual manner.

Mounted on the crank case A preferably between the working cylinders is a vertical cylinder E, see Figs. 5 and 6, which is provided with inlet ports E' and E² which are covered by connections F and F', the connection F having a pipe which leads to a carburetor F², see Fig. 1, of ordinary construction. The connections F and F' are connected by means of a vertical tube F³, adapted to conduct explosive gas from the connection F to the connection F', as hereinafter described.

The tube F³, see Figs. 7 and 8 is provided with an inclined plate f at its upper end, which plate f is provided with alternate ridges f' and grooves f², and is perforated with holes f³ through the ridges f'. As shown in Figs. 7 and 8 the tube F³ is turned with the high point of the inclined plate f toward the carburetor F².

This tube F³ can be turned in the connections F and F' to adjust the inclined plate f in the upper end thereof, with reference to the incoming gas, so that the proper quality of gas is admitted to the lower inlet port

⁵ E² of the cylinder E. The cylinder E is also provided with outlet ports G and G' which are covered by connections G² and G³ to which ducts H and H' are secured which lead to the inlet ports e of the working cylinders C of the engine.

Within the cylinder H is placed a sleeve valve J which is closed at each end, and is provided with ears J' on the bottom thereof to which a pitman J² is pivoted, the lower end of which is mounted on a crank J³ on the crank-shaft B'. The sleeve valve J is provided with inlet ports j and j', and with outlet ports j² and j³. Within the sleeve valve J is placed a piston K, which is provided with pins K' which extend outwardly through slots in the walls of the sleeve valve J, and cylinder E, and pivoted on said pins K' are pitmen K² which extend to and are mounted on cranks K³ on the crank-shaft B'.

²⁵ The crank J³ causes sufficient reciprocal movement of the valve sleeve J to cause the inlet and outlet ports j and j' and j² and j³ to alternately coincide for the inlet and outlet of gas from the carburetor F². The cavity within the sleeve valve J is of less length than the travel of the piston K, but the throw of the crank J³ is sufficient to move said sleeve sufficiently to permit the full travel of the piston K therein.

³⁰ L indicates paddle wheels mounted on the crank shaft B' adapted to throw oil from the pan A² into the lower end of the cylinder E to keep it lubricated.

While I have shown cranks K³ and J³ to operate the sleeve valve J and piston K, the same result could be secured by substituting eccentrics in place thereof.

⁴⁰ In operation, see Figs. 5 and 6, the crank-shaft B' turning in the direction of the arrow, the crank J³ being located in advance of the crank K³ on the crank shaft, the sleeve valve J has moved downward far enough to close the outlet port G, while the crank K³ is at its top center, which places the piston K at its highest point. When the piston K starts its downward travel, the sleeve valve J moves simultaneously in the same direction, but because the crank K³ has greater throw than the crank J³, the piston K moves faster than the sleeve valve J, thereby arriving at the lower end of the sleeve valve J when said valve has past and closed the outlet port G' in the cylinder E on the upward movement thereof. The piston K moving downward within the sleeve valve, reduces the pressure within the upper end of said valve, so that when the port j in the wall of the sleeve valve J coincides with the inlet port E' in the cylinder E gas from the carburetor F² will rush into said sleeve valve above said piston, and on the return movement of said piston K and sleeve valve said gas will be compressed, and

when the outlet ports G and j² coincide, will flow through the duct H into the working cylinder C connected therewith, the incoming gas in said working cylinder being deflected by the deflector c² blows the consumed gas therein out through outlet port e'. Upon the upward movement of the piston K, gas is drawn into the sleeve valve J below said piston through the inlet port E² when the port j' coincides therewith which will be forced through the outlet ports j³ and G' when they coincide at the return movement of said piston and sleeve valve, and into the duct H', and thence into the corresponding working cylinder.

At each reciprocation of the piston K a measured volume of gas is drawn from the carburetor F² into the sleeve valve J, and then forced into the working cylinder when the piston therein is at its lower point.

It will be obvious that the sleeve valve J and piston K are operated by eccentric mechanism on the crank shaft, and that there is no other valve mechanism.

Having thus fully shown and described the construction and operation of my invention so that others can utilize the same, I do not desire to be limited to the exact construction shown and described, as many modifications and alterations can be made therein without departing from the scope of my invention, therefore what I claim as new and desire to secure by Letters Patent is:

1. In a device of the class described, a working cylinder having inlet and outlet ports, a crank shaft, a working piston in said working cylinder adapted to control said inlet and outlet ports, another cylinder having inlet and outlet ports, a sleeve within said last mentioned cylinder having closed ends and having inlet and outlet ports in the wall thereof adapted to alternately coincide with said inlet ports and to alternately coincide with said outlet ports, a piston within said sleeve, crank and pitman mechanism operated by said crank-shaft to reciprocate said sleeve, and another crank of greater diameter and pitman mechanism operated by said crank shaft to reciprocate said piston within said sleeve to force a measured volume of gas into said working cylinder at each revolution of said crank shaft.

2. In a device of the class described, a pair of working cylinders having piston controlled inlet and outlet ports, a cylinder having inlet and outlet ports, ducts connecting said outlet ports with said inlet ports in said working cylinders, a sleeve valve having closed ends and having inlet and outlet ports in the wall thereof adapted to coincide with the inlet and outlet ports in said cylinder during the reciprocation thereof, a crank shaft, crank and pitman mechanism operated by said crank shaft to recip-

- rotate said sleeve valve, a piston within said sleeve valve, and crank and pitman mechanism operable by said crank shaft to reciprocate said piston simultaneously and with relation to said sleeve valve, whereby measured volumes of gas will be alternately drawn into each end of said sleeve valve and forced through said ducts into said working cylinders.
3. In an internal explosive engine comprising a working cylinder having inlet and outlet ports, a crank-shaft, and a piston adapted to control said ports, of another cylinder having inlet and outlet ports through the wall thereof adjacent to oppo-
- site ends thereof, a closed ended sleeve valve in said cylinder having inlet and outlet ports through the wall thereof, a piston in said sleeve valve, crank and pitman mechanism to operate said sleeve valve, another crank and pitman having longer throw, to operate said piston, ducts connecting the inlet ports of the working cylinder, with the outlet ports of said second named cylinder, whereby gas may be alternately drawn into said sleeve valve and forced therefrom into said working cylinder.

In testimony whereof I affix my signature.

WILLIAM N. TITUS.
